UNITED STATES PATENT OFFICE

JOSEPH R. WARNER, OF FORT WAYNE, INDIANA, ASSIGNOR TO S. F. BOWSER & COMPANY, INC., OF FORT WAYNE, INDIANA, A CORPORATION OF INDIANA

LUBRICATOR

Application filed March 9, 1927. Serial No. 173,859.

This invention relates to a device for supplying lubricating material to various forms of mechanism requiring lubrication, and has for one of its objects the provision of a lubricating pump which shall be simple and economical to manufacture, efficient in operation, and of improved construction.

A further object is to provide an air release for the pressure cylinder of the pump which will prevent pumping air to the discharge pipe and prevent excess pressure in the cylinder at the time of intake.

Other objects and advantages will appear from the following description and claims.

15 The invention is exemplified in the combination and arrangement of parts shown in the accompanying drawings and described in the following specification, and it is more particularly pointed out in the appended 20 claims.

In the drawings—

Fig. 1 is a longitudinal sectional view through an oil tank having a number of pumping units applied thereto;

25 Fig. 2 is a section through one of the pumping units at right angles to Fig. 1; and

Fig. 3 is a section substantially on line 3—3 of Fig. 2.

The numeral 10 designates a suitable tank 30 for lubricating material having a screen intake 11 through which the tank is filled. A shaft 12 extends longitudinally of the tank 10 and is journaled in a bearing member 13 at one end of the tank. The opposite end 35 of the shaft is supported on a stud shaft 14 journaled in a bearing member 15 mounted in the end of the tank opposite the member 13. The shaft 12 is provided with a ratchet wheel 16 having teeth 17 on the inner face 40 thereof which are engaged by pawls 18 carried by a disc 19 secured to the stud shaft 14. The stud shaft 14 is oscillated by a lever 20 which may be connected to any suitable drive. The connection is preferably with 45 the machine to which lubricant is supplied so that the speed of oscillation may be proportional to the speed of the machine to which lubricant is furnished. Holding dogs 21 are pivoted on the bearing support 15 to 50 prevent reverse rotation of the ratchet wheel

16. The ratchet mechanism operates in the lubricating material within the tank 10 so that it is thoroughly lubricated at all times. A series of lubricating units or pumps 22 extend through openings in the top of the tank 10 and are operated by cams 23 on the shaft 12. The construction and operation of the units 22 will be best understood from Fig. 2 of the drawings.

Each unit comprises a body 24 which is secured to the top of the tank by bolts which extend through openings 25 in the body 24 and the top of the tank 10. A cup or recess 26 is formed in the upper portion of the body 24 and is provided with a cover plate 27 resting on the rim of the recess. The cover plate 27 is held in place by a cap 28 and a shouldered length of tubing 29, both threaded into the body 24, as shown in Fig.

2. The lower end of the tube 29 communicates with a recess 30 in the body 24 while the upper end extends through a cap 31 which covers a glass cylinder 32 which is set over an opening 33 in the cover plate 27 above the cup 26. The cap 31 is provided 75 with a circumferential recess 34 surrounding the tube 29 and a perforation 35 through the wall of the tube provides communication between the inside of the tube and the recess 34. A drain passage 36 connects the recess 34 with a drip spout 37 at the upper end of the glass cylinder 32. A cap 38 is threaded on the upper end of the tube 29 and holds the cover cap 31 in place. The body member 24 is perforated to receive a 80 tube 39, the upper end of the tube being threaded and held in place by an adjusting nut 40. The nut 40 is disposed within the cup 26 and is provided with a shoulder which bears against the interior face of the 85 plate 27. The lower end of the nut rests upon the surface of the body 24. It will be apparent that rotation of the nut 40 will adjust the pipe 39 vertically relative to the body 24. The pipe 39 is provided with a slot 41 which communicates through an opening 42 in the passage 30 and the interior of the tube 29. A threaded pin 43 extends into the slot 41 and prevents rotation of the tube 39. The body 24 is provided with a cylin-

drical opening 44 arranged parallel with the opening for the tube 39. A piston 45 is slidably mounted in the cylinder 44.

A reciprocating head 46 is slidably mounted on the lower end of the tube 39 and is provided with a recess 47 for receiving an extension 48 on the lower end of the piston 45. The extension 48 is provided with a peripheral groove 49 which registers with a pin 50 for retaining the extension 48 within the recess 47. The extension 48 fits loosely within the recess 47 to prevent binding of the piston 45 in its cylinder in case the movement of the head 46 is not exactly in alinement with the axis of the cylinder 44. The head 46 engages one of the cams 23 on the shaft 12 and is held in contact with the face of the cam by springs 51 and 52. It will be apparent that the head 46 will be lifted by the cam 23 at each revolution of the shaft 12 and will be returned by the force of the springs 51 and 52. If in any case a positive action in both directions is required the head 46 may be provided with a second contact face at the opposite side of the cam 23 from that shown in the drawings so that the head will be positively moved in both directions by the cam 23. This construction may be found desirable for some installations. The lower end of the perforation in the head 46 in which the tube 39 is located is closed by a plug 53 and a port 54 is provided at one side of the opening for the tube 39. 55 is a plug for closing an opening at the opposite side of the tube 39 formed in boring the port 54. A valve 56 is disposed within the tube 39 near the lower end thereof and is held by a spring 57 against a stop pin 58. A plug 60 forms an abutment for the opposite end of the spring 57. The tube 39 is slotted at 61 to provide passage for lubricating material past the plug 60. When the head 46 is moved downwardly the port 54 will clear the lower end of the tube 39 and since the downward movement of the head will tend to form a vacuum in the lower end of the tube 39, the lubricating material will rush in through the port 54 and fill the lower end of the tube 39 and the space within the head 46 below the lower end of the tube. When the head 46 starts its upward movement the port 54 will be closed by the lower end of the tube 39 and the lubricant in the lower end of the tube will be thus entrapped. Upward movement of the head 46 will force the entrapped lubricant to open the valve 56 and the lubricant will be caused to flow through the slot 61 past the plug 60 and into the upper portion of the tube 39. Each stroke of the head 46 will introduce a new charge of oil into the tube 39 so that the oil will be pumped to the top of the tube 65 and will pass through the opening 42 into

the passage 30 and through the pipe 29 and opening 35 into the drain spout 36, from which it will drop through the sight tube 32 into the cup 26. This provides a sight feed for the lubricating device in which the oil falls freely through the sight feed at atmospheric pressure. The cover 31 for the sight feed 32 may be perforated to insure atmospheric pressure within the sight feed and cup 26. 75

The oil drains from the cup 26 through ports 62 to the cylinder 44. The lower ends of these ports will be closed when the head 46 is in its upper position, as shown in Fig. 2, but when the head moves downwardly the piston 45 will uncover the ports 62 and draw the lubricant from the ports into the cylinder above the end of the piston 45. The movement of the lubricant is effected both by gravity and by the reduced pressure produced by the downward movement of the piston 45 in the cylinder 44. A port 63 connects the upper end of the cylinder 44 with a chamber 64 closed by a cap 65. A hollow valve 66 is slidably mounted in an opening in the head 24 communicating with the chamber 64 and is held downwardly by a spring 67 contained in a fitting 68 to which a discharge tube 69 is connected. The tube 69 leads to the mechanism to be lubricated. 95 The side of the valve 66 is provided with a perforation 70 which is carried upwardly to discharge lubricant into the fitting 68 when the pressure in the chamber 64 becomes sufficient to compress the spring 67. 100

An arrangement is provided for connecting the upper end of the cylinder 44 to atmosphere at the limit of the discharge stroke of the piston 45. The upper end of the piston 45 is provided with a projection 105 71 through which a perforation 72 extends. The lower end of the perforation 72 communicates through a lateral opening 73 with a peripheral groove 74 in the piston 45. A port 75 opens into the cup 26 above the liquid level in the cup and communicates with the interior of the cylinder 44 through a lateral passage 76. At the upper end of the movement of the piston 45 the peripheral groove 74 registers with the passage 110 76 which thus connects the upper end of the cylinder 44 to atmosphere. This arrangement relieves any pressure in the air pocket at the top of the cylinder 44 at the end of the compression stroke, thus insuring the formation of a partial vacuum during the intake stroke of the piston. This, of course, facilitates the entrance of the lubricating material from the cup 26 when the port 62 is uncovered. If the increased pressure were not relieved at the end of the discharge stroke of the piston, it is possible that there would still be more than atmospheric pressure when the piston reaches the end of its intake stroke. This would cause the escape 115 120 125 130

of air or oil through the port 62 and interfere with the entrance of oil from the cup 26. The arrangement has the further decided advantage of preventing building up sufficient air pressure in the cylinder 44 to cause air to be pumped into the line 69. As a matter of practice it is desirable for the discharge cylinder 44 to have a greater capacity than the supply pump which supplies the lubricant to the cup 26. It is not practical to make the two operate exactly the same and if lubricant were supplied to the cup 26 faster than it is discharged therefrom the cup, of course, would be caused to run over. For this reason the capacity of the discharge pump is made greater than that of the supply pump so that there is no danger of overflowing the cup 26. From this it follows that there will not be sufficient oil in the cup 26 to supply the cylinder 44 and some air will be introduced when the port 62 is uncovered. If no means were provided for removing this air it would be pumped into the lubricating line and thus interfere with the operation of the lubricating system.

The amount of oil pumped is controlled by raising and lowering the pipe 39 so as to control the amount of travel past port 54 of piston 39. These parts may be adjusted to supply only a fraction of the capacity of the discharge pump so that, except for the air release, considerable quantities of air might be pumped into the lubricating line. The space at the end of the cylinder 44 is so proportioned to the stroke of piston and the strength of the spring 69 that when the chamber 64 is filled with oil the compression produced within the cylinder is not sufficient to force any of the air over into the chamber 64 and through the valve 66. When the pump is first put into operation before the chamber 64 has been filled with oil, the introduction of oil under pressure will force the initial charge of air in the chamber 64 out through the pipe 69, but after this initial charge of air has once been removed, no further air will be discharged into the lubricating system.

I claim:—

1. Pumping apparatus having a pumping chamber therein, means for alternately expanding and contracting said chamber to effect intake and discharge of fluid to be pumped, and means for connecting said chamber to the atmosphere after said chamber has been contracted and before it begins to expand.

2. Pumping apparatus comprising a body member having a pumping chamber therein provided with intake and discharge ports, means for alternately expanding and contracting said chamber and for opening said intake port when said chamber is expanded and closing said intake port during con-

traction of said chamber, and means for subjecting the interior of said chamber to atmospheric pressure at the beginning of an expansion of said chamber but closing said chamber to atmosphere during expansion thereof.

3. Pumping apparatus comprising a body member having a pumping chamber therein provided with intake and discharge ports, means for closing said discharge port during the expansion of said chamber to permit reduction of pressure in said chamber by the expansion thereof, and means for connecting said chamber to atmosphere at the beginning of the expansion thereof to relieve excess pressure therein.

4. Pumping apparatus comprising a body member having a pumping chamber therein provided with air space in the upper portion thereof and provided with an intake port adjacent the lower portion thereof, means for expanding and contracting said pumping chamber and for opening said intake port when said chamber has been expanded to admit fluid into said chamber to be pumped, and means for connecting said air space to atmosphere at the beginning of the expansion of said chamber to insure an initial pressure equal to that of the atmosphere at the beginning of the expansion of said chamber.

5. Pumping apparatus comprising a cylinder having a piston arranged to reciprocate therein, a receiving chamber below the upper end of said cylinder and connected thereto by a passageway, means for closing the upper end of said cylinder and providing an air pocket at the upper end of said cylinder above said receiving chamber so that the pumped liquid will flow downwardly from the upper end portion of said cylinder through said passageway into said receiving chamber, a check-valve for controlling flow of liquid from said receiving chamber to the discharge port, means for directing the liquid into said cylinder when the piston is at the lower end of its stroke, and means for relieving the pressure in said air pocket by connecting the same to the atmosphere when said piston is at the upper end of its stroke.

6. A lubricator comprising a container for a lubricant, pumping apparatus for supplying lubricant to said container, additional pumping apparatus for withdrawing lubricant from said container and discharging the lubricant to apparatus to be lubricated, said additional pumping apparatus having a greater capacity than the apparatus for supplying lubricant to said container, and means for periodically connecting the interior of said additional pumping apparatus directly to atmosphere to prevent discharge of air with the lubricant discharged from said additional pumping apparatus.

7. A lubricator comprising a member having a container for lubricant, said container being open to atmosphere, a pump for supplying lubricant to said container, a discharge pump for receiving lubricant from said container and discharging it to apparatus to be lubricated, and means for connecting the interior of said discharge pump directly to atmosphere between discharge and intake operations thereof. 10
8. A lubricator comprising a body member having a container therein for a lubricant, said container being open to atmospheric pressure, a pump for discharging lubricant from said container to apparatus to be lubricated, said pump comprising a cylinder having a reciprocating piston therein, and means for connecting the interior of said cylinder to atmosphere at the close of each discharge stroke of said piston. 15
9. A lubricator comprising a body member having a container for lubricant therein, said container being open to atmosphere, a sight feed, means for supplying lubricant to said container through said sight feed, a reciprocating pump for discharging lubricant from said container to apparatus to be lubricated, said reciprocating pump comprising a cylinder having a piston and an intake port communicating with said container and a discharge port, means for reciprocating said piston to effect intake and discharge of lubricant to and from said cylinder, and means for connecting the interior of said cylinder with atmosphere at the close of a discharge stroke of said piston. 25
10. A lubricator comprising a pump having a cylinder and a piston arranged to reciprocate therein, said pump having intake and discharge ports, and a supplemental port for connecting the interior of said cylinder with atmosphere at the close of a discharge movement of said piston. 40
11. A lubricator comprising a pump having an upright cylinder and a piston arranged to reciprocate in said cylinder, said pump having an intake and a discharge port, and a supplemental port opening through the upper end of said piston for connecting said cylinder with atmosphere at the close of a discharge stroke of said piston. 45
12. A lubricating pump comprising a cylinder and a piston arranged to reciprocate in said cylinder, said cylinder having an air pocket at one end thereof, and an extension on the end of said piston arranged to enter said air pocket at the close of a discharge stroke of said pump, said piston having a port therein opening through said extension and arranged to register with a port in said cylinder communicating with atmosphere when said piston reaches the end of its discharge stroke to bring said extension into said air pocket. 55
13. A lubricator comprising a body mem- 60
ber having a tube extending therefrom, a head arranged to reciprocate on said tube, means operated by said head for pumping lubricant through said tube, said body member having a cylindrical chamber therein, a piston arranged to reciprocate in said chamber, and a movable connection between said piston and head for operating said piston from said head. 70
14. A lubricator comprising a body member having a recess therein, a tube extending from said body member, a head arranged to reciprocate on said tube, means operated by said head for pumping lubricant through said tube into said recess, said body member having a cylindrical opening therein, and a port connecting said recess with said opening, and a piston arranged to reciprocate in said opening said piston having movable connection with said head to operate said piston from said head and compensate for slight variations in the position of said piston relative to said head. 75
15. A lubricator comprising a receptacle for a lubricant, a body member mounted on said receptacle, a tube connected with said body member and extending into said receptacle, said body member having a recess therein, a head slidably mounted on said tube, means for reciprocating said head on said tube, valve mechanism for controlling the passage of lubricant through said tube, a sight feed interposed between said tube and recess to disclose the flow of the lubricant from said tube into said recess, said body member having a cylindrical opening therein, a piston arranged to reciprocate in said opening, said opening being connected with said recess by an intake port, said body member having a discharge port communicating with said cylindrical opening, said piston having a port therein opening at the upper end thereof and arranged to register with a port in said body member communicating with atmosphere when said piston is in its uppermost position, and a spring-held valve for closing said discharge port. 90
16. Lubricating apparatus comprising pumping mechanism having a predetermined capacity, a receptacle for receiving lubricant from said pumping mechanism, a sight-feed between said pumping mechanism and said receptacle and connected to the atmosphere, additional pumping mechanism of larger capacity than said first-named pumping mechanism, an additional receptacle for receiving the lubricant from said additional pumping mechanism, an automatic check-valve for controlling the flow of lubricant from said additional receptacle, means comprising an intake port for directing lubricant from said first-named receptacle to said additional pumping mechanism, and means for venting said additional pumping mechanism to said first- 105
- 110
- 115
- 120
- 125
- 130

named receptacle and thence to the atmosphere when said additional pumping mechanism is about to effect an intake operation.

17. In a lubricator, a receptacle, a pumping unit mounted on the receptacle for extracting a lubricant therefrom, a pump piston, a reciprocating head for actuating said pump piston, a movable connection between said piston and said reciprocating head to compensate for variations in the alinement of the head and piston, positive means for reciprocating said head in one direction, and a spring tension device for moving the head in the opposite direction.
18. A lubricator comprising a lubricant receptacle and a pumping unit for extracting a lubricant therefrom, said pumping unit comprising a sight feed, means for delivering lubricant above the sight feed and flowing the same therethrough by gravity, a cylinder having a reciprocating piston therein, means for collecting the lubricant from the sight feed and delivering the same to said cylinder, said sight feed being open to atmospheric pressure, and a communication between the sight feed and the top of the cylinder for opening the cylinder to atmospheric pressure comprising an axial bore in said piston, an annular recess around said piston communicating with said axial bore, a conduit communicating with said annular recess, and a conduit extending from said first-mentioned conduit and terminating above the level of the lubricant flowing from the sight feed.

In testimony whereof I have signed my name to this specification on this 4th day of March, A. D. 1927.

JOSEPH R. WARNER.
